GARMENT HANGER

Helen L. Stein, 1331 E. 12th St., Des Moines, Iowa

Filed Nov. 22, 1965, Ser. No. 88,185

Term of patent 14 years

(Cl. D80—8)

I claim:

The ornamental design for a garment hanger, substantially as shown.
